COMBINED HAIR CURLER AND COMB

Joseph Lloyd Chiariello, Los Angeles, Calif.

Application June 26, 1956, Serial No. 42,054

Term of patent 14 years

(Cl. D86—10)

FIG. 2.

FIG. 1.

FIG. 3.

The characteristic features of my design reside in the portions shown by means of full lines in the drawing.

I claim:

The ornamental design for a combined hair curler and comb, as shown and described.
